ARTHUR J. MURRAY, OF MINNEAPOLIS, MINNESOTA

COMBINATION FEEDER AND SHIPPING CARTON

Application filed July 23, 1932. Serial No. 624,242.

This invention relates to an improved combination feeder and shipping carton, and has as an object, to provide such a device of simple and inexpensive construction, which may 5 readily be manufactured at a small cost.

A further object is to provide a combination feeder and shipping carton comprising an outer enclosing member or supporting carton having an insert mounted therein, opposite portions of which are shaped to provide 10 a hopper bottom, and other wall portions having suitable feed openings therein, means being provided for closing said apertures, when the device is being used as a shipping 15 carton, and portions of opposite walls of the enclosing member being perforated to permit the detachment of portions of said walls whereby access may be had to the feed openings in the walls of the insert. 20 A further object is to provide an insert of the class described, comprising a blank provided with suitable score lines for dividing it into a plurality of sections, whereby said sections may be folded to provide the bottom 25 and side walls of the insert, and other wall members being secured to the opposite edges of said blank adapted to be folded upwardly to provide the end walls of the insert, said side walls, end walls, and bottom cooperating 30 to provide a suitable container adapted to be fitted into a suitable supporting carton.

Other objects of the invention reside in the particular construction of the insert, whereby it may be quickly set up to form a container; in the means provided at the edges 35 of the side and end wall members of the insert whereby said members may be interlocked at the corners of the insert to retain said members in position; in the arrangement 40 of the feed openings and the means provided in the bottom of the insert for diverting the contents of the insert outwardly beneath said feed openings; and in the simple construction of said insert whereby it may be quickly 45 folded from a blank, into a container adapted to be fitted into a suitable enclosing member or carton which functions to retain the walls of the insert in operative positions, and also as a shipping box or carton.

50 Other objects of the invention will appear

from the following description and accompanying drawings and will be pointed out in the annexed claims.

In the accompanying drawings, there has been disclosed a structure designed to carry 55 out the various objects of the invention, but it is to be understood that the invention is not confined to the exact features shown as various changes may be made within the scope of the claims which follow. 60

In the drawings:

Figure 1 is a view showing the improved chick feeder and shipping box filled and ready for shipment;

Figure 2 is a view showing one of the 65 side walls of the enclosing member or carton having a portion of a wall thereof, removed, whereby access may be had to the feed openings formed in a wall of the insert;

Figure 3 is an enlarged cross-sectional 70 view on the line 3—3 of Figure 2, showing the interior construction of the insert;

Figure 4 is a view showing the insert partially inserted within the enclosing member;

Figure 5 is a view showing the insert 75 removed from the enclosing member; and

Figure 6 is a view showing the blank from which the insert is formed before the wall portions thereof are folded.

The combination feeder and shipping carton disclosed in this invention is shown comprising an outer enclosing member or carton 2, having end walls 3 and side walls 4. The upper portion of the carton is formed with a plurality of flaps 5 and 6 adapted to be 80 folded, one over the other, to provide a closure for the carton, as shown in Figures 1 and 2. A suitable binding strip 7 may be provided for securing the flaps in closed position.

An important feature of this invention resides in the construction of the insert 8 provided within the carton 2. This insert is best illustrated in Figures 5 and 6, and comprises side walls 9 and end wall members 11. The side walls 9 are shown integrally formed 85 with a bottom section 12, whereby the wall sections 9 and bottom section 12 may be formed from an integral piece of material, cut out in the form of a blank, as shown in Figure 6. The opposite edges of the side wall 90

sections 9 are shown provided with tabs 13 which are divided from the main sections 9 by suitable score lines 14 so that said tabs may be bent at right angles to the wall sections 9, as shown in Figure 5. Suitable recesses 15 and 16 are also provided in the opposite edges of the wall sections 9 for purposes which will subsequently be described.

The end wall members 11 are preferably shaped as shown in Figure 6, and are recessed at their upper portions, as indicated at 17 to provide shoulders 18. The opposite edges of these wall members are shaped as shown, to provide inclined edges 19 and 21, which provide supports for a hopper bottom which will subsequently be described. The end wall members are here shown secured to suitable tabs 22 provided on the bottom section 12, by such means as staples 23. If desired, they may be stitched or gummed thereto.

The blank constituting the side wall sections 9 and the bottom member 12 are provided with suitable score lines 24, 25, 26, 27, 28, and 29, along which score lines, the material is bent or folded when the insert 8 is set up, as shown in Figure 5. Before the end wall members 11 are secured to the bottom member 12, the blank from which the wall sections 9 and bottom member 12 are formed, is bent along the score lines 28, 29, and 28, as shown in Figure 6, and the end wall members 11 are then secured to the tabs 22, whereby a V-shaped spreader 31 will be formed in the section 12 constituting the bottom of the insert, as clearly shown in Figures 3 and 6.

The end wall members 11 are next folded upwardly into vertical positions, as shown at the right hand side of Figure 6, and the side wall sections 9 are then folded or bent along the lines 24, 25, 26, and 27, so that the edge portions 32 and 33 of the opposite edges of the wall sections 9, will seat against the inclined edges 19 and 21 of the end wall members 11, as clearly illustrated in Figure 5. The tabs 13 at the upper portions of the wall sections 9 are then bent to the positions shown in Figure 5, so that they will fit against the outer faces of the end walls 11 and will be supported upon the shoulders 18, whereby the upper portions of the side wall sections 9 will be held in their respective positions with relation to the end wall members 11. If desired, the tabs 13 may be secured to the end wall members, but this has been found unnecessary, because when the insert is fitted into the carton 2, the wall sections 9 and 11 will be retained in their proper places by the walls of the carton, so that they cannot be come disarranged.

By folding or bending the wall sections 9 along the score lines, as above described, the wall sections 34 bounded upon opposite sides by the score lines 24 and 25, will cooperate to provide a hopper bottom for the insert.

The wall sections 35, between the score lines 25 and 26, when the insert is set up, will be disposed at an incline, as shown in Figures 3 and 5. These wall sections 35 are provided with a plurality of feed openings 36 through which the feed or material contained in the insert may be removed by the chicks or poultry, as will readily be understood by reference to Figure 2.

To prevent the material from spilling from the insert when the carton is being shipped from one place to another, a suitable sealing strip 37 is secured to each inclined wall section 35 to seal the feed openings 36, as shown in Figure 5. This sealing strip may readily be detached from the wall sections 35 to expose the openings 36, when the box has been converted into a feeder, as shown in Figure 2.

To convert the device into a feeder, the side walls 4 of the carton are shown provided with panels 38, defined by rows of perforations 39 and 41 along which the material may readily be severed or torn for the purpose of removing said panels to gain access to the feed openings 36, as shown in Figure 2. Short rows of perforations 42 are provided at one end of each panel 38 between which suitable instructions may be printed for removing the panels 38 from the carton. By means of these short rows of perforations 42, an attendant may, by the pressure of a thumb, detach the wall portion bounded by the rows of perforations 41 and 42, after which he may readily insert a finger and detach the entire panel from the wall 4. After the panels 38 have been detached from the carton, the sealing strips 37 may readily be removed from the inclined wall portions 35, whereupon the material in the insert will be exposed through the feed openings 36, as shown in Figure 2.

The novel apparatus herein disclosed has been found very useful as a combined feeder and shipping carton. The insert 8 provided within the carton, greatly strengthens the latter so that it may readily be handled in transit without danger of damaging the carton or box to cause leakage of the material therefrom. The end walls 11 of the insert are preferably made from a slightly heavier material than the side wall sections 9 but, in some cases, it may be desired to make all of the wall members of the same weight of material.

The inclined edges 21 of the side walls 11 provide supports for the inclined wall sections 35 so that when the device is set up, as shown in Figures 1, 2, and 3, and the box is converted into a feeder, the exposed wall sections 35 will be supported against downward pressure by the inclined edges 21 of the end walls. The shoulders 18 provided at the upper portions of the end walls 11 are engaged by the tabs 13 and provide suitable supports therefor, so that the upper portions of the side walls cannot become disarranged.

with respect to the end wall members 11. It will also be noted by reference to Figure 3, that the spreader 31 provided in the bottom of the insert will divert the material outwardly beneath the feed openings 36, so that the chicks may readily reach all of the material in the insert whereby the latter may be completely emptied of its contents by the chicks or poultry.

10 It is also to be noted that by constructing the insert as shown in Figures 5 and 6, the inserts may be stacked in bundles, while in the form of blanks, thereby requiring very little storage space, when not set up for use. 15 The cartons 2 are constructed in the usual manner whereby they may be packed or stored, when empty, in a collapsed or knocked down condition.

I claim as my invention:

20 1. In a device of the class described, an outer inclosing member, an insert removably fitted into said enclosing member and comprising a plurality of walls, one of which has a feed opening therein, means on said 25 walls for retaining them in operative positions when the insert is fitted into said enclosing member, said means being dependent upon the walls of the outer enclosing member for their operation, and means by which said 30 feed opening may be exposed to convert the device into a feeder.

2. In a device of the character described, an outer enclosing member, an insert removably fitted into said enclosing member and comprising a plurality of walls, one of which has a feed opening therein, means on said 35 walls adapted for interlocking engagement to retain them in operative positions when the insert is fitted into said enclosing member, 40 said means being dependent upon the walls of the outer enclosing member for their operation, and means in a wall of the outer enclosing member by which said feed opening may be exposed to convert the device into a feeder.

45 3. In a device of the character described, an outer enclosing member, an insert fitted into said enclosing member and comprising a plurality of walls, one of which has an inclined portion providing a hopper bottom, a 50 portion of a wall of said insert beneath said hopper bottom having a feed opening therein, means at the upper portions of the walls of said insert adapted for interlocking engagement to retain said walls in operative 55 positions, when the insert is fitted into said enclosing member, and a portion of one of the walls of the outer enclosing member being detachable whereby said feed opening may be exposed to convert the device into a feeder.

60 4. In a combination feeder and shipping carton, an outer enclosing member, an insert adapted to be supported in said enclosing member and having opposite walls thereof provided with inclined portions cooperating 65 to provide a hopper bottom, other inclined

wall portions disposed below said hopper bottom and having suitable feed openings therein, detachable means for closing said feed openings when the device is in transit prior to being converted into a feeder, and means in opposite walls of said outer enclosing member by which access may be had to said feed openings.

5. In a combination feeder and shipping carton, an outer enclosing member, an insert adapted to be supported in said enclosing member and having opposite walls thereof provided with inclined portions cooperating to provide a hopper bottom, other inclined wall portions connected with the wall portions forming said hopper bottom and having suitable feed openings therein, sealing strips for closing said feed openings when the device is in transit prior to being converted into a feeder, and means in opposite walls of said outer enclosing member by which access may be had to said feed openings.

6. In a combination feeder and shipping carton, an outer enclosing member, a separable insert adapted to be fitted into said enclosing member, the side walls of said insert having portions inclined inwardly to provide a hopper bottom, other portions of said side walls being inclined in the opposite direction and being connected with said first mentioned inclined portions, said second mentioned inclined wall portions having suitable feed openings therein through which the contents of the insert may be removed when the device is used as a feeder, means for temporarily closing said feed openings when the apparatus is in transit, and suitable perforations in opposite walls of the enclosing member adapted to register with the lower inclined wall portions of the insert, whereby the wall portions bounded by said perforated lines may be detached to gain access to the feed openings.

7. In a combination feeder and shipping carton, an outer enclosing member open at the top and provided with suitable flaps whereby said top may be closed, an insert adapted to be fitted into said member and comprising side walls, end walls and a bottom wall, means whereby said side and end walls may be interlocked at the corners of the insert to retain said walls in their respective positions, means on certain of said walls extending inwardly and cooperating to provide a hopper bottom, whereby all of the material in the insert will feed towards the center thereof, said certain walls also having other inclined wall portions provided with suitable feed openings, and means at the bottom of the insert for diverting the material outwardly beneath said feed openings.

8. In a combination feeder and shipping carton, a carton open at the top and provided with suitable flaps whereby said top may be closed, an insert adapted to be fitted into

said opening and providing side walls, end walls, and a bottom wall, means whereby said side and end walls may be interlocked at the corners of the insert to retain said walls in their respective positions, when the insert is supported in the carton, the side walls of said insert having portions bent inwardly and outwardly to provide a hopper bottom and also to provide inclined walls having feed openings therein, sealing strips for closing said feed openings when the apparatus is filled and not in use, and means in the side walls of the carton by which certain portions of said walls may be detached from the carton to gain access to the insert, and whereby said sealing strips may be removed to uncover the feed openings.

9. An insert adapted to be supported in an outer enclosing member, said insert being formed from a blank of sheet material having suitable score lines therein whereby it may be folded to provide a plurality of upright walls, means by which portions of certain of said upright walls may be folded to provide a hopper bottom for the insert thus formed, and means for retaining the walls of the insert in position.

10. An insert adapted to be supported in an outer enclosing member, said insert being formed from a blank of sheet material having suitable score lines therein whereby the opposite end portions of said blank may be folded to provide the side walls of the insert, end wall members attached to said blank and adapted to fold upwardly to provide the end walls of the insert, and means on said end wall members adapted to interlock with means on said side wall members to retain said side and end walls in position.

11. An insert adapted to be supported in an outer enclosing member, said insert being formed from a blank of sheet material having suitable score lines therein whereby the opposite end portions of said blank may be folded to provide side members of a container, oppositely extending tabs on said side wall members, end wall members attached to the intermediate portion of said blank and

adapted to be folded upwardly to provide the end walls of the container, recesses in the opposite edges of each end wall member adapted to receive the tabs on said side wall members to retain said walls in their respective positions, means whereby portions of said side wall members may be bent inwardly to provide a hopper bottom, and also to provide inclined wall portions having feed openings therein, and means at the edges of said side wall members adapted for interlocking engagement with the edges of said end wall members to support said inclined apertured wall portions and also the wall portions forming said hopper bottom.

12. An insert adapted to be supported in an outer enclosing member, said insert being formed from a blank of sheet material having a plurality of score lines, therein dividing the same into a plurality of sections, the intermediate or bottom section of said blank being adapted to fold to provide a V-shaped bottom adapted to be engaged by and divert material supported in the insert outwardly, the end wall sections of said blank being adapted to fold upwardly to provide the side walls of the insert, end wall members secured to the opposite edges of said bottom section and adapted to fold upwardly to provide the end walls of the insert, said end walls being provided at opposite intermediate portions with inclined edges and at their upper portions with oppositely disposed recesses, tabs on the upper portions of said side wall sections adapted to be received in said recesses, and other portions of said side wall sections being bent inwardly along certain of said score lines to provide a hopper bottom for the insert thus formed, and also to provide inclined wall sections having suitable feed openings therein, the inclined edges of said end wall members forming supports for the inwardly bent portions of the side wall members.

In witness whereof, I have hereunto set my hand this 13 day of July 1932.

ARTHUR J. MURRAY.
